(57) **CLAIM**

The ornamental design for a resistance band sleeve, as
shown and described.

DESCRIPTION

FIG. 1 is a front perspective view of my design for a
resistance band sleeve;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side elevation thereof.

The broken lines in figures 1, 4, 5, 6 and 7 represent a design
element and form part of the claim.

1 Claim, 7 Drawing Sheets
